UNITED STATES PATENT OFFICE

JOHN J. PALOTCE, OF YOUNGSTOWN, OHIO

PLIERS, ETC.

Application filed February 18, 1931. Serial No. 516,714.

This invention is a novel improvement in pliers, tongs, tweezers, and the like, such as shown in U. S. Letters Patent No. 1,772,428 issued to me on August 5, 1930; and the objects of the invention are broadly to provide improved means for automatically locking the jaws in engagement with the work in any position of the handles; also to provide manually operable means for releasing the locking means when it is desired to open the locked jaws; also means for maintaining the releasing means ineffective; also to provide a combination tool of the plier type carrying on one of the handles a pivoted hammer head adapted to be swung from inoperative position between the handles into various operative positions with respect to the axis of the tool and retained in such position thereby permitting the tool to be used as an ordinary hammer when the handles are drawn together and locked.

A further object is to provide a combined reamer, pliers, wire-cutter, screw driver and hammer into a single compact, substantially symmetrical tool.

Other minor objects of the invention will be hereinafter set forth.

I will explain the invention with reference to the accompanying drawings which illustrates several practical embodiments thereof to enable others to adopt and use the same; and will summarize in the claims the novel features of construction, and novel combinations of parts, for which protection is desired.

In said drawings:

Fig. 1 is a side elevation, partly in section, showing the preferred form of my invention; and indicating various positions of the hammer head.

Fig. 2 is a section on the line 2—2, Fig. 1.

Fig. 3 is a section on the line 3—3, Fig. 1.

Fig. 4 is a section on the line 4—4, Fig. 1.

Fig. 5 is a side elevation, partly in section, showing a modified form of my invention.

Fig. 6 is a section on the line 6—6, Fig. 5.

Fig. 7 is a section on the line 7—7, Fig. 5.

Fig. 8 is an end elevation of the pliers showing the hammer head in folded inoperative position.

My invention is illustrated in connection with a pair of pliers having work engaging jaws A, A preferably of the reamer type having reaming cutters A' on their outer surfaces, said jaws being operated by cross-handles B and C, pivoted at D, the handles being normally yieldably urged to open the jaws by a spring E interposed between the handles adjacent pivot D. Jaws A, A may if desired be provided with opposed wire cutting blades A². My invention however is not to be limited to use on pliers of the type herein illustrated, for obviously same may be readily adapted for use in connection with other types of pliers, tongs, tweezers, and various other gripping tools.

As shown one of the handles, B, is provided with a pivoted arcuate tongue 1 extending through a slot 2 in the other handle C, said handle C being preferably materially thickened in depth as at C' adjacent the slot. Slot 2 is provided with an arcuate rear wall 2a lying adjacent the outer periphery of tongue 1, and with a forwardly inclined front wall 2b forming an upwardly flaring recess with the inner periphery of the arcuate tongue 1, the lower end of the inclined wall 2b of slot 2 terminating adjacent the inner periphery of the tongue. A wedging ball 3 is contained in the slot 2, operated in grooves 1a and 2a in the tongue 1 and inclined wall 2b of slot 2 respectively, said ball 3 being normally yieldably urged downwardly into wedging position at the lower end of the slot against the inner periphery of arcuate tongue 1 by means of a flat spring 4 interposed between the ball 3 and a removable plate 6 on the upper face of the handle C covering the slot 2, the cover plate 6 being provided with an opening for the passage of the arcuate tongue 1 therethrough.

Manually operable means are also provided for raising and thereby releasing ball 3 from locking engagement, the particular means shown in Figs. 1—4, inclusive comprising a wedge bolt member 9 slidably mounted in a bore extending through the enlarged portion C' of handle C below the ball 3, said bolt 9 also extending through an elongated slot 1b (Fig. 4) in the tongue 1 and into a

recess in the inclined wall of the slot 2. The outer wedge shaped end 9a of bolt 9 is tapered downwardly to underlie the ball 3 as shown in Fig. 1. When the bolt 9 is moved forwardly (or to the left, Fig. 1) the outer wedge shaped end 9a will raise ball 3 against the action of spring 4 out of lowered wedging position and maintain the ball raised so that handles B and C may be operated freely without permitting ball 3 to lock the handles; but if bolt member 9 is moved rearwardly (or to the right, Fig. 1) the wedge shaped end 9a will be retracted so as to release ball 3 and permit the ball to drop into wedging position assisted by the spring 4. For operating the bolt member 9 I preferably provide a trigger 7 pivotally mounted as at 7a on a stud 10 tapped into the portion C' below the end of bolt member 9, said trigger 7 having a slotted hinged connection with the end of the bolt member 9 so that a pull rearwardly on the trigger will shift bolt 9 to hold the ball 3 in raised position, and a forward push on the trigger will release the ball.

Means are also provided for yieldably retaining the bolt member 9 in adjusted position, which means, as illustrated in Figs. 1-4 inclusive consists of a spring 11 housed in a bore 11a extending down through the enlarged portion C' of the handle C and communicating with the bore or the wedge-shaped bolt member 9. In the lower end of the bore 11a I place a ball 12 seating upon the bolt member 9 (Fig. 1) said ball 12 being urged downwardly by spring 11 into frictional engagement with the bolt member 9 to yieldably hold the member 9 in any position to which the latter is adjusted. The spring 11 is retained in its bore 11a by the cover member 6.

In operation, if it is desired that the pliers shall retain their grip upon the work which is gripped in the jaws A—A, the trigger 7 should be pushed forwardly to shift the bolt member 9 away from the arcuate tongue 1 so as to permit the ball 3 to drop into lowered position. Ball 12 will then slide along the inner periphery of tongue 1 as the handles B and C are being closed together, but if attempt is made to open the handles the ball 3 will immediately wedge between the inclined wall 2b of the recess and the arcuate tongue 1 and thus prevent opening of the handles until the wedge-shaped bolt 9 has been shifted forwardly by trigger 7 sufficiently to raise ball 3 out of wedging contact as hereinbefore explained.

In Figs. 5, 6, 7, a modification is illustrated, of the means for raising and releasing ball 3 from its locking engagement. In this modification the trigger member 7 itself extends into slot 2 and underlies the ball 3, the trigger 7 being pivotally mounted upon a pin 7a journaled between the walls of a slot C² in the lower end of enlarged portion C' of handle C, said slot C² extending into the

slot 2. A trip 7b is provided for trigger 7 whereby when the trip is pulled by the finger of the person using the tool the trigger will raise ball 3 against the action of spring 4 and maintain the ball so elevated that handles B and C may be operated freely without bringing ball 3 into locking engagement. When the trigger 7 is pulled rearwardly and released a flat spring 13 (Fig. 6) due to side pressure on 7b and walls of slot C² hold the ball 3 raised out of locking position. When the trigger 7 is pushed forwardly then the ball 3 will be urged downwardly by spring 4 to bind or wedge between the inclined wall 2b of slot 2 and the inner periphery of the arcuate tongue 1. In this modification the tongue 1 need not be slotted as the ball operating means does not extend through the tongue.

Hence, if it is desired that the pliers shall retain their grip upon the work held in the jaws A—A, the trigger 7 should be set so that the ball 3 will slide along the inner periphery of tongue 1 as the handles B, C are being closed together, but if attempt is made to open the handles the ball 3 will immediately wedge between the inclined wall 2b and the arcuate tongue 1 and thus prevent opening of the handles until the trigger 7 has been shifted sufficiently to raise ball 3 out of wedging contact.

The outer end of handle C is preferably formed with an edge C³ adapted to be utilized as a screw-driver. The outer end of the handle B is provided with an offset disk like portion B³ (Fig. 8) adapted to enter the bifurcated end 8a of a hammer head 8 pivoted as at 8b on the disk portion B³, whereby the hammer 8 may be swung from inoperative position (shown in full lines in Figs. 1 and 5 parallel with and between the handles B and C) into the operative positions shown in dotted lines. When the hammer head 8 is in use the handles B and C, must of course be locked in fully closed position by the ball 3. The hammer head 8 is yieldably retained in any of the positions shown in Figs. 1 and 5 by means of a bolt 8c sliding in a bore 8d in hammer 8, said bolt 8c being normally urged outwardly by a coiled spring 8e so as to enter notches B⁴ in the periphery of disk like portion B³. Other locking means for the hammer head may be employed.

I do not limit my invention to the exact forms shown in the drawings for obviously changes may be made therein within the scope of the claims.

I claim:

1. A tool having gripping jaws and operating handles, one of the handles having a slot having an inclined wall; a tongue on the other handle extending through said slot; a ball in the slot adapted to wedge against the tongue; means for yieldably urging the ball into wedging position; and a pivoted trig-

- ger whereby when the trigger is actuated the ball will be held out of wedging engagement with the tongue; and yieldable means for maintaining the trigger in adjusted position.
5. In a tool as set forth in claim 1, a wedge shaped member underlying the ball and slidably mounted in a bore in the handle, said member extending through a slot in the tongue; and said trigger operating the member.
10. 3. A tool having gripping jaws and operating handles, one of the handles having a slot; a tongue on the other handle sliding in said slot; a ball in the slot adapted to normally wedge against the tongue to prevent separation of the handles; and trigger means entering the slot and engaging the ball adapted when operated to hold the ball out of wedging position.
20. 4. In a tool as set forth in claim 3, said tongue having a slot; and a wedge operated by the trigger underlying the ball and slidably mounted in a bore in the handle, said wedge extending through the slot in the tongue.
25. 5. In a tool as set forth in claim 3, said trigger means entering the slot and underlying the ball whereby as the trigger is actuated the ball will be lifted; and a member yieldably engaging the trigger for maintaining same in adjusted position.

JOHN J. PALOTCE.
